UNITED STATES PATENT OFFICE.

CYRUS W. CHAMBERS AND WILLIAM H. CHAMBERS, OF CEDAR RAPIDS, IOWA.

ADJUSTABLE SILO-ROOF.

1,105,402.

Specification of Letters Patent.

Patented July 28, 1914.

Application filed May 15, 1912. Serial No. 697,548.

To all whom it may concern:

Be it known that we, CYRUS W. CHAMBERS and WILLIAM H. CHAMBERS, citizens of the United States, residing at Cedar Rapids, in the county of Linn and State of Iowa, have invented a certain new and useful Adjustable Silo-Roof, of which the following is a specification.

Our invention provides for the adjustability of the triangular roof sections used in this class of silos, thus permitting them to fit the silo without necessarily having been made to accord to its diameter, and also for the self-adjustment in the assemblage of the sections to each other so that when the roof is closed their edges shall be accurately jointed, thus preventing cutting and minimizing the amount of time employed in erection.

20 Further objects are to utilize the full capacity of the tank after shrinkage or settling of the silage, and to allow ready access to the interior of the tank.

Figure 1 shows in part a plan view partly in section of our improved roof mounted upon a circular silo of usual type, two roof sections being seen in open position, and other sections in closed position. Fig. 2 shows a vertical central sectional view on the line 2--2 of Fig. 1, also indicating two adjustable roof sections as open, and '10 a netting as hereinafter described. Fig. 3 shows in detail our improved hinge arrangement as applied to the silo proper and a roof section. Figs. 4, 5 and 6 show detached views of our hinge.

Referring to the drawings, 1 represents a portion of the silo proper and upon it is mounted a series of rafters 2. These having the top edge of the silo tank as a base rise to an apex. Hinged at or near the top of the silo tank are roof sections 3 the number of which is governed by the diameter of the silo. These sections when closed are supported by the rafters 2, and when opened are held in a substantially vertical position by means of the projections 4 abutting against the upper part of the silo tank. The roof sections 3, as in Figs. 1 and 2, on being raised to vertical position, allow the silage to be thrown over them, and when the silage has settled the roof sections are lowered so as to be supported by the rafters, thus forming a complete and well constructed roof.

In order to allow for the adjustability of the roof sections and to permit them to fit silos of varying diameters, we employ hinges of particular construction to attach the roof sections to the silo tank as shown generally in Figs. 1 and 2, and in detail in Fig. 3. The hinge is composed of two members 5 and 6, the former being attached to the inner side of the lower end of a roof section, and the latter to the silo near its top. The mode of attachment of the hinge to the silo and roof is shown in Figs. 1, 2 and 3. In the upper member of the hinge is a slot 7 in which fits the squared portion 8 of a bolt 9, thus fastening said member to a roof section 3. The lower member 6 of the hinge is attached near the upper edge of the silo. The upper member 5 is fitted to the part 6 by means of the pin 10 of the latter which enters the hole 11 of the former. The roof sections are now snugly fitted upon the rafters, and by means of the bolts 9 are fastened to the hinge parts 5. The squared part 8 of the bolt 9 resting in the slot 7 prevents the bolt 5 from turning while adjustments are made.

Referring to Fig. 4, it will be seen that the member 5 of the hinge has angular relation with respect to its fellow member 6, this angularity conforming to that of the side of the triangular section. Though the member 5 has this angular relation to the member 6, the pivot pin 10 connecting the two members is at a right angle to the member 6, and therefore the pivotal movement on said pin is the same as though the two members of the hinge occupied parallel relations to each other. But inasmuch as the slot 7 has the same angularity as that of its member 5 and is of considerable length, as shown in Figs. 4 and 5, it is apparent that the roof section 3 is capable of different adjustments whereby the sides of the sections may be accurately fitted with respect to each other. Thus, in the fitting of the triangular sections to the silo, assuming that the bolt 9 is free to slide in the angular slot 7 of the hinge member 5, when the series of triangular sections have been practically brought to closed position each section is free to adjust itself, in a plane or direction parallel to the slot, with respect to its contiguous section, the settling which effects the fit being therefore automatic; and after the edges of the

respective sections have been accurately brought together the adjustment is made permanent by the tightening of the nuts of the bolts 9. Owing to this adjustability the 5 series of individual sections of the roof may be accurately jointed and brought to proper position regardless of the diameter of the silo.

It will be seen that in the adjustment of 10 any one of the series of roof sections no change is made in its angularity with respect to that of the remaining sections, the sliding of any one section upon another in the 15 adjustment being in the line of the common angularity of the roof, which is therefore preserved at all times, with the result that the roof is always flat, unbroken by undulations and consequently tight.

The roof sections are preferably made of 20 galvanized sheet metal, but may be of wood or other suitable material.

It is well known that the shrinkage or settling of the silage is great, amounting in 25 a silo of ordinary size to many cubical feet, and to compensate for this we use an open topped wire netting 12 as shown in part in Fig. 2. This netting, which is suitably supported by the tank, incloses the open spaces 30 between the vertically-standing roof sections, and provides a space which may be filled before the shrinkage or settling of the silage has occurred. After the silage in the 35 space inclosed by the wire netting has settled the farmer may then close the roof sec-

Having thus described our invention, what we claim is:—

1. In a silo tank, the combination of 40 rafters rising to an apex, a series of triangular roof sections hinged to the upper portion of said tank, each roof section being unconnected with any other, hinges for each roof section, one member of each hinge being fixedly attached to said tank and the other member slotted and adapted to be adjustably secured to a roof section near the base thereof, a bolt for each hinge passing through the slotted member thereof and through the roof section, and means associated with said bolt for clamping said roof 50 section to said slotted member, the construction being such that on loosening the bolt of each of its hinges vertical or lengthwise adjustment may be made of said roof section without changing the line of angularity 55 common to itself and the remaining roof sections, substantially as set forth.

2. The combination of a silo tank having 60 rafters running therefrom to an apex, a plurality of substantially triangular roof sections hinged to the upper portion of the tank, each section being slidably adjustable on its hinges independently of and in the pitch of the adjacent sections, substantially as set forth.

CYRUS W. CHAMBERS.
